UNITED STATES PATENT OFFICE.

HENRY J. GAISMAN, OF NEW YORK, N. Y.

WOVEN ELASTIC FABRIC.

SPECIFICATION forming part of Letters Patent No. 783,628, dated February 28, 1905.

Application filed February 4, 1903. Serial No. 141,791.

To all whom it may concern:

Be it known that I, HENRY J. GAISMAN, a citizen of the United States, and a resident of New York city, borough of Manhattan, New York, have invented certain new and useful Improvements in Woven Elastic Fabrics, of which the following is a specification.

The object of my invention is to provide a fabric adapted to cling or adhere to a contiguous surface to retard slipping thereover; and to this end the invention comprises the novel details of improvement that will be more fully hereinafter set forth and then pointed out in the claims.

Reference is to be had to the accompanying drawings, forming part hereof, wherein—

Figure 1 is a face view of a piece of fabric embodying my invention. Fig. 2 is an exaggerated view of part thereof. Fig. 3 is a perspective view of a hose-supporter comprising my improved fabric. Fig. 4 is a similar view of a garter, and Fig. 5 is a perspective view illustrating a method of manufacturing the fabric.

In the accompanying drawings similar characters of reference indicate corresponding parts in the several views.

In the drawings the numeral 1 indicates generally my improved fabric, comprising strands of threads interwoven with elastic strips or warps 2 in such manner that portions of the latter will be on one side of a line passing centrally across the fabric, and preferably such portions of the elastic warps will be exposed on the surface of the fabric. The elastic strips or warps 2 are shown extending parallel with the fibrous or cotton warps 3, and in producing the exposed portions of the elastic or rubber strips in the fabric I have illustrated a certain number or series of the weft threads at 4, crossing over portions of certain rubber strips and beneath other rubber strips, and another series of weft-threads at 4^a, crossing under certain of the first-mentioned rubber strips and over certain of the second-mentioned rubber strips, and so on alternately throughout the various series of weft-threads, thereby producing interspersed rubber warp portions 2^a, exposed on one surface of the fabric, and such exposed warp portions are at one side of the fabric, and thus have a tendency

to curl the fabric like a spring. The projecting portions 2^a of the rubber strips or bands 2 being interspersed upon the surface of the fabric present a gripping or friction medium 55 superior to that produced by fibrous threads alone where rubber strips are wholly embedded beneath the surface of the threads or strands in well-known elastic fabrics.

In Fig. 5 is illustrated a manner of weaving the fabric to produce the results described, a short and narrow portion of the fabric being shown, the weft-threads being shown as woven in pairs. In this illustrative form of my invention between each two rubber warps 2 are 60 located four fibrous or cotton warps 3, and one pick 4 of weft-threads, starting at a, passes over a rubber warp 2^b, over and under all cotton warps 3, as shown, over the rubber warps 2^c and 2^d, under rubber 2^e, and over 2^f, and 65 thence in the return said weft passes around and under the outer rubber warp 2^f and under 2^e, 2^d, 2^c, and 2^b, passing from a under and over the cotton warps 3, as shown. The weft is similarly woven for a certain number of 70 picks—say ten, (in series of five pairs of picks)—exposing for a certain length at 2^a part of the rubber warp 2^e, so that such part is unconfined. The next similar series of picks—say ten—alternate in their passage 75 with respect to warps 2^c and 2^e—that is to say, the weft passes under rubber warp 2^c and over and under 2^e, exposing at 2^a part of warp 2^e, but out of line transversely with the exposed part of 2^e, the weft passing under and 80 over the cotton warps, as shown. In Fig. 2 thirteen rubber warps are shown, while in Fig. 5 but five such warps are shown for purposes of illustration. The weft-threads pass around the rubber warps at the edges of the 85 fabric, and each second rubber warp has certain portions exposed, and the intermediate rubber warps are all interwoven with the weft. In the example illustrated a certain series of weft-threads pass over three rubber warps 90 and under the fourth rubber warp, and the next series of weft-threads pass over three other rubber warps and under the corresponding fourth rubber, and so on alternately, whereby each second rubber warp has portions exposed, but out of transverse line with the adjacent exposed rubber, resulting in producing 95 100

transverse lines of exposed rubber, the adjacent lines alternating in position in the longitudinal direction of the fabric. Exposed rubber warps are thus interspersed over the surface of the fabric.

It will be obvious that the particular manner of weaving shown and the relative locations of the exposed rubber warps may be altered, as more or less of the rubber warps may be exposed and the alternating arrangement of the exposed portions 2^a may be changed. In Figs. 1 and 2 fibrous warps have been omitted for the purpose of illustration, it being understood that the number of fibrous warps may be varied to suit requirements. The elastic warps at the selvage are not shown as exposed, the weft binding them in. It will be observed that certain portions of the weft pass under all the rubber warps, whereby the rubber warps are concealed when the warp is beaten upon the side opposite the exposed portions 2^a, as in Figs. 2 and 3.

With the elastic fabric above described it will be apparent that as the exposed rubber portions or projections come in contact with a surface against which they are presented the rubber will have a tendency to cause the elastic fabric to cling or adhere thereto more or less by frictional contact. Furthermore, as the rubber strips or bands are offset more or less from the transverse central line of the fabric they have a tendency to cause the fabric to bend or curl in the nature of a spring, or, in other words, the fabric tends to bend in the direction toward which the exposed rubber projects.

My improved elastic fabric will be found useful in various relations, such, for instance, as in hose-supporters, garters, suspenders, and the like. In Fig. 3 I have shown the fabric applied in a hose-supporter, and thereby when the fabric is fastened around a leg the exposed rubber at 2^a and the spring-like action will tend to prevent the supporter from slipping down the leg. In Fig. 4 the elastic fabric is shown applied in the form of a garter and with the like effect of keeping it from slipping on the leg, and if used as an armlet it will similarly tend to keep in place upon the arm. When the fabric is used in suspenders, the exposed rubber warps and the spring-like action will tend to maintain the suspenders in proper position upon the shoulders of the wearer.

55 The manner of placing the rubber strips in the fabric, so as to produce the projecting or exposed portions, and the relative positions and number of the latter, as well as the cross-section or shape of the warps and other details, may be altered without departing from the spirit of my invention.

Having now described my invention, what I claim is—

1. As a new article of manufacture, a woven fabric having lines of exposed rubber surfaces

interspersed on the face of the fabric, the exposed rubber surfaces of one line alternating with the exposed rubber surfaces of another line, substantially as described.

2. As a new article of manufacture, a woven elastic fabric having lines of interspersed rubber surfaces projecting beyond the surface of fibrous threads of the fabric, the exposed rubber surfaces of one line alternating with the exposed rubber surfaces of another line, substantially as described.

3. As a new article of manufacture, a woven elastic fabric having elastic warps extending longitudinally of the fabric and intermeshing with the fibrous weft of the fabric that extends substantially perpendicularly to the elastic warps, said weft passing under and over certain of said warps producing exposed and concealed portions of said elastic warps, substantially as described.

4. As a new article of manufacture, a woven elastic fabric having parallel rubber warps intermeshing with certain weft-threads, series of weft-threads also passing under and over certain rubber warps to produce exposed and concealed portions thereof, substantially as described.

5. As a new article of manufacture, a woven elastic fabric having parallel rubber warps intermeshing with the weft-threads of the fabric, one series of weft-threads passing under and over certain rubber warps and an adjacent series of weft-threads passing over and under the corresponding rubber warps providing exposed and concealed portions of said warps, interspersed exposed portions of said rubber warps being thus presented outwardly on the face of the fabric, substantially as described.

6. As a new article of manufacture, a woven elastic fabric having rubber warps, portions of said rubber warps being alternately exposed and concealed on one face in the direction of their length by the weft, said rubber warps being concealed by the weft on the opposite face, substantially as described.

7. A woven elastic fabric comprising longitudinally-disposed elastic and fibrous warps and fibrous weft, the weft passing under and over the fibrous warps and under portions of the elastic warps exposing such portions of the latter on one face of the fabric, substantially as described.

8. A woven elastic fabric comprising longitudinally-disposed elastic and fibrous warps and fibrous weft, the weft passing under and over the fibrous warp and under portions of the elastic warps in the same line and under and over intermediate elastic warps, exposing portions of the elastic warps, substantially as described.

HENRY J. GAISMAN.
